UNITED STATES PATENT OFFICE

2,447,835

ROCKING INNER-JAW END WRENCH

Jonathan H. Beard, Beaumont, Tex.

Application May 26, 1947, Serial No. 750,590

5 Claims. (Cl. 81—92)

1

The invention concerns a pawl actuated end wrench for use in adjusting nuts, studs and the like.

It is an object of the invention to provide an end wrench suitable for use in relatively inaccessible places and where space is limited.

It is a further object of the invention to provide an end wrench adapted to adjust a nut or a stud without removing the wrench therefrom.

Another object of the invention is to provide an end wrench which is simple and sturdy in construction and requires little or no maintenance, and in which parts subject to wear may be readily replaced.

The invention will be understood by referring to the following description and the accompanying drawing, in which:

Fig. 1 is a front view showing one end of the wrench.

Fig. 2 is a right end view as seen from the line 2—2 of Fig. 1.

Fig. 3 is an enlarged front view of a pawl which constitutes a portion of the device as illustrated in Fig. 1.

Fig. 4 is a right end view of a pawl as seen from the line 4—4 of Fig. 3.

Fig. 5 is a left end view as seen from the line 5—5 of Fig. 3.

Fig. 6 shows a modified form of the pawl as illustrated in Fig. 3.

Referring to the drawing, the wrench comprises a handle 1 having a ring 2 formed on one end thereof adapted to encircle a polygonal fastening device such as a nut or a stud. A pawl 3 is pivotally mounted on one side of the ring 2 adjacent the handle 1.

The pawl 3 is fulcrumed intermediate its ends and has a tooth-like end portion 4 adapted when in an operative position to extend inwardly toward the center of the ring to engage the fastening device and a bifurcated end portion including a pair of jaws 5 adapted to straddle the adjacent portion of the handle 1. The handle 1 has a flattened portion 6 adjacent the ring 2.

The ring 2 and the adjacent portion of the handle 1 have a notch 7 formed therein adapted to receive the pawl 3. One side of the notch 7, indicated by the numeral 8, is straight and parallel to the center line of the handle 1 and the other side of the notch 7, indicated by the numeral 9, is curved. The surface of the pawl 3 intermediate the jaws 5, indicated by the numeral 10, is curved in the same direction as the curved surface 9 of the notch 7 but on a shorter radius. Optionally one or both of the surfaces 9 and 10

2

may be straight, for example, rather than curved. The arrangement is such that the pawl 3 may be rocked back and forth in the notch 7. The straight side 8 of the notch 7 is adapted to limit rotation of the pawl 3 in one direction.

A pair of lugs 11 extend inwardly from the ends of the jaws 5. A pair of grooves 12 formed in the handle 1 on opposite sides thereof are adapted to receive the lugs 11 and to retain the pawl 3 in engagement with the handle 1. The grooves 12 are curved and the arrangement is such that the lugs 11 slide in the grooves 12 as the pawl 3 is rocked in the notch 7.

The pawl 3, which is subject to wear, may be readily replaced. In assembling the wrench the jaws 5 of the pawl 3 may be spread apart momentarily and the bifurcated end of the pawl 3 may be snapped in place over the adjacent portion of the handle 1 with the lugs 11 slidably engaging the grooves 12. Similar procedure may be followed upon removing the pawl 3. The walls of the jaws 5 may be thinned to increase the flexibility thereof and to facilitate spreading them apart. Optionally the jaws 5 may be clamped in place, with or without heating. If desired the lugs 11 may be eliminated and the jaws 5 may be deformed at their ends to engage the grooves 12. Holes may be drilled in the jaws 5 and screws, pins or rivets may be inserted therein as substitutes for the lugs 11. A single slot extending thru the handle 1 may be substituted for the grooves 12.

A pair of lugs 13 positioned on opposite sides of the handle 1 are adapted to engage the ends of the jaws 5 to further limit rotation of the pawl 3 in one direction.

A groove 14 extends across one edge of the handle 1 and across a pair of lugs 15 positioned on opposite sides of the handle 1 adjacent the edge thereof. A hairpin shaped wire spring 16 is receivable in the groove 14 and extends inwardly from the edge of the handle 1 on opposite sides thereof. The ends of the spring 16 engage the jaws 5 of the pawl 3 to yieldably maintain the pawl 3 in engagement with the straight side 8 of the notch 7. Retaining grooves 17 are provided in the ends of the jaws 5 to receive the ends of the spring 16.

The arrangement is such that the pawl 3 remains fixed in an operative position when the wrench is turned in one direction and is rotated to an inoperative position against the resistance of the spring 16 when the wrench is turned in the opposite direction. In the modification shown in Fig. 6 the tip of the end portion 4, in-

dicated by the numeral 18, is knurled rather than pointed as in the arrangement shown in Fig. 3.

The invention may be modified in various ways without departing from the spirit and scope thereof.

I claim:

1. An end wrench comprising a handle having a ring formed on one end thereof adapted to encircle a polygonal fastening device, a pawl pivotally mounted on one side of the ring adjacent the handle, the pawl being fulcrumed intermediate its ends and having a tooth-like end portion adapted when in an operative position to extend inwardly toward the center of the ring to engage the fastening device and having a bifurcated end portion including a pair of jaws adapted to straddle the adjacent portion of the handle, the handle having a flattened portion adjacent the ring, the ring and the adjacent portion of the handle having a notch formed therein adapted to receive the pawl, one side of the notch being straight and parallel to the center line of the handle, the arrangement being such that the pawl may be rocked back and forth in the notch, the straight side of the notch being adapted to limit rotation of the pawl in one direction, a pair of grooves formed in the handle on opposite sides thereof adapted to be engaged by the ends of the jaws to retain the pawl in engagement with the handle, the grooves being curved and the arrangement being such that the ends of the jaws slide in the grooves as the pawl is rocked in the notch, and means for yieldably maintaining the pawl in engagement with the straight side of the notch.

2. An end wrench comprising a handle having a ring formed on one end thereof adapted to encircle a polygonal fastening device, a pawl pivotally mounted on one side of the ring adjacent the handle, the pawl being fulcrumed intermediate its ends and having a tooth-like end portion adapted when in an operative position to extend inwardly toward the center of the ring to engage the fastening device and having a bifurcated end portion including a pair of jaws adapted to straddle the adjacent portion of the handle, the handle having a flattened portion adjacent the ring, the ring and the adjacent portion of the handle having a notch formed therein adapted to receive the pawl, one side of the notch being straight and parallel to the center line of the handle, the arrangement being such that the pawl may be rocked back and forth in the notch, the straight side of the notch being adapted to limit rotation of the pawl in one direction, a pair of lugs extending inwardly from the ends of the jaws, a pair of grooves formed in the handle on opposite sides thereof adapted to receive the lugs and to retain the pawl in engagement with the handle, the grooves being curved and the arrangement being such that the lugs slide in the grooves as the pawl is rocked in the notch, and means for yieldably maintaining the pawl in engagement with the straight side of the notch.

3. An end wrench comprising a handle having a ring formed on one end thereof adapted to encircle a polygonal fastening device, a pawl pivotally mounted on one side of the ring adjacent the handle, the pawl being fulcrumed intermediate its ends and having a tooth-like end portion adapted when in an operative position to extend inwardly toward the center of the ring to engage the fastening device and having a bifurcated end portion including a pair of jaws adapted to straddle the adjacent portion of the

handle, the handle having a flattened portion adjacent the ring, the ring and the adjacent portion of the handle having a notch formed therein adapted to receive the pawl, one side of the notch being straight and parallel to the center line of the handle, the arrangement being such that the pawl may be rocked back and forth in the notch, the straight side of the notch being adapted to limit rotation of the pawl in one direction, a pair of lugs extending inwardly from the ends of the jaws, a pair of grooves formed in the handle on opposite sides thereof adapted to receive the lugs and to retain the pawl in engagement with the handle, the grooves being curved and the arrangement being such that the lugs slide in the grooves as the pawl is rocked in the notch, a pair of lugs positioned on opposite sides of the handle adapted to engage the ends of the jaws to further limit rotation of the pawl in one direction, and means for yieldably maintaining the pawl in engagement with the straight side of the notch.

4. An end wrench comprising a handle having a ring formed on one end thereof adapted to encircle a polygonal fastening device, a pawl pivotally mounted on one side of the ring adjacent the handle, the pawl being fulcrumed intermediate its ends and having a tooth-like end portion adapted when in an operative position to extend inwardly toward the center of the ring to engage the fastening device and having a bifurcated end portion including a pair of jaws adapted to straddle the adjacent portion of the handle, the handle having a flattened portion adjacent the ring, the ring and the adjacent portion of the handle having a notch formed therein adapted to receive the pawl, one side of the notch being straight and parallel to the center line of the handle, the arrangement being such that the pawl may be rocked back and forth in the notch, the straight side of the notch being adapted to limit rotation of the pawl in one direction, a pair of lugs extending inwardly from the ends of the jaws, a pair of grooves formed in the handle on opposite sides thereof adapted to receive the lugs and to retain the pawl in engagement with the handle, the grooves being curved and the arrangement being such that the lugs slide in the grooves as the pawl is rocked in the notch, a pair of lugs positioned on opposite sides of the handle adapted to engage the ends of the jaws to further limit rotation of the pawl in one direction, and a spring secured to the handle and engaging the jaws of the pawl to yieldably maintain the pawl in engagement with the straight side of the notch.

5. An end wrench comprising a handle having a ring formed on one end thereof adapted to encircle a polygonal fastening device, a pawl pivotally mounted on one side of the ring adjacent the handle, the pawl being fulcrumed intermediate its ends and having a tooth-like end portion adapted when in an operative position to extend inwardly toward the center of the ring to engage the fastening device and having a bifurcated end portion including a pair of jaws adapted to straddle the adjacent portion of the handle, the handle having a flattened portion adjacent the ring, the ring and the adjacent portion of the handle having a notch formed therein adapted to receive the pawl, one side of the notch being straight and parallel to the center line of the handle, the arrangement being such that the pawl may be rocked back and forth in the notch, the straight side of the notch being adapted to limit rotation of the pawl in one direction, a pair of lugs extending inwardly from the ends of the

jaws, a pair of grooves formed in the handle on opposite sides thereof adapted to receive the lugs and to retain the pawl in engagement with the handle, the grooves being curved and the arrangement being such that the lugs slide in the grooves as the pawl is rocked in the notch, a pair of lugs positioned on opposite sides of the handle adapted to engage the ends of the jaws to further limit rotation of the pawl in one direction, a groove extending across one edge of the handle and across a pair of lugs positioned on opposite sides of the handle adjacent the edge thereof, and a hairpin shaped wire spring receivable in the last mentioned groove and extending inwardly from the edge of the handle on opposite sides thereof, the ends of the spring engaging the jaws of the pawl to yieldably maintain the pawl in engagement with the straight side of the notch.
